Fig. 5

FIG. 1 is a side elevation of a tea cart showing our new design;

FIG. 2 is a front elevation thereof;

FIG. 3 is a rear elevation thereof;

FIG. 4 is a plan view thereof; and

FIG. 5 is a perspective view thereof.

The dominant features of the design reside in the provision of large wheels supported in spaced relation below the bottom shelf at the forward end thereof on the rearwardly bent lower end of the front shelf-supporting frame as shown.

We claim:

The ornamental design for a tea cart, as shown and described.
